WIRE CUTTER

Martin L. Rowe, Chicago, Ill., assignor to The
Gerrard Company, Inc., Chicago, Ill., a corpo-
ration of Delaware

Application May 22, 1936, Serial No. 81,220

2 Claims. (Cl. 30—1)

When newspapers are sent out to the news dealers, they are usually tied up in bundles with wires which keep the papers from getting separated and also prevent unauthorized removal of 5 any of the papers. The dealers, upon receipt of the bundles, have to cut the wire before they can get any of the papers out, and this cutting is usually done with pliers.

Even the cheapest pliers which can be used for 10 this work cost quite a bit, and as it is customary to furnish the dealers with pliers and a large number are required, this represents a substantial item of expense. Furthermore, pliers have to be turned into just the right position before they can 15 be used to twist and break a wire, which takes up time and delays to that extent the opening of the bundles. Moreover, as pliers are used for many other different purposes, they are likely to be misplaced, and experience has shown they are frequently not at hand when needed for this purpose.

The object of the present invention is to provide a wire cutting device which is simple, light and compact, can be used to sever wire when held in any position between the fingers, will do the work easily and quickly, costs practically nothing to manufacture, and is likely to be available for use at all times due to its convenient size and lack of utility for other purposes.

A preferred embodiment of the invention is 30 presented herein for the purpose of exemplification, but it will of course be understood that the invention is susceptible of embodiment in other slightly modified structural forms coming equally within the scope of the appended claims.

In the accompanying drawing:

Fig. 1 is a perspective view of a bundle of newspapers tied with wire;

Fig. 2 is a face view of the cutter; and

Fig. 3 is an edge view of the cutter.

The cutter which is shown in the drawing consists of a hardened metal disk 10 which is provided about its periphery with a number of uniformly spaced radial slots 11. The disk is provided at its center with an aperture 12 which facilitates centering of the disk between the fingers and allows the disk to be either hung over a hook or strung on a cord.

The disk is preferably about 1 3/4 inches in diameter and 3/16 inch in thickness, with the slots 50 about 1/8 inch in length and .049 inch in width, but dimensions other than these can of course be employed. Slots of this particular size will work

effectively with 17 1/2 or 18 gauge wire, which is the wire usually employed in the bundling of newspapers.

When newspapers are tied into a bundle by means of wire, one wire 13 is placed about the 5 bundle lengthwise of the same and a second wire 14 is placed about the bundle at right angles to the first wire. The stacked papers are compressed somewhat by the wires, which are tied under tension. Both of the wires of course have 10 to be removed in order to permit the free removal of the papers.

With the slotted disk 10 the cutting of the wires is a simple matter. The disk is grasped in any position between the thumb and forefinger, and the rounded edge of the disk beyond the thumb is 15 pressed against the bundle with the nearest slot 11 straddling the wire to be severed. The papers in the bundle will yield enough to allow the wire to be bottomed in the slot without difficulty, and when the disk is now twisted briskly first in one direction and then in the other through but a portion of a turn the tensioned wire will immediately snap. The curvature of the edge of the 20 disk at opposite sides of the particular slot used presents a blunt nose to the papers, which eliminates the likelihood of digging into and injuring the outermost paper, which damage is of frequent 25 occurrence when ordinary pliers are used.

I claim:

1. A one-piece wire cutter comprising a single 30 thin flat metal disk which is provided about its periphery with a number of radial slots and is characterized by opposed finger-engaging surfaces by means of which the disk may be gripped adjacent any one of the slots and twisted back 35 and forth with considerable leverage whereby to cause a wire positioned in such adjacent slot to be broken by the abrupt bending to which it is subjected by the edges of the slot.

2. A one-piece wire cutter comprising a single 40 thin flat centrally apertured metal disk of circular form which is provided about its periphery with a number of uniformly spaced radial slots and is characterized by opposed finger-engaging 45 surfaces by means of which the disk may be gripped adjacent any one of the slots and twisted back and forth with considerable leverage whereby to cause a wire positioned in such adjacent slot to be broken by the abrupt bending to which 50 it is subjected by the edges of the slot.

MARTIN L. ROWE.
